United States Patent Office

Des. 179,444

Patented Dec. 25, 1956

179,444

AIRCRAFT NAVIGATION INSTRUMENT

Edward R. Dayton, Huntington Station, Grant W. Schleich, Huntington, and Eugene F. Reedy, Merrick, N. Y., assignors to Sperry Rand Corporation, Great Neck, N. Y., a corporation of Delaware

Application October 28, 1955, Serial No. 38,612

Term of patent 14 years

(Cl. D52—6)

FIG. 1.

FIG. 2.

Fig. 1 is a front elevation view of an aircraft navigation instrument showing our new design; and

Fig. 2 is a side elevational view thereof.

The dominant features of our design are those portions of Figs. 1 and 2 shown in solid lines. The lining on the drawing represents contrasting color areas.

We claim:

The ornamental design for an aircraft navigation instrument, as shown and described.
